UNITED STATES PATENT OFFICE.

DONALD F. WHITING, OF NEW YORK, N. Y., ASSIGNOR TO WESTERN ELECTRIC COMPANY, INCORPORATED, OF NEW YORK, N. Y., A CORPORATION OF NEW YORK.

RADIO APPARATUS.

Application filed November 4, 1924. Serial No. 747,704.

This invention relates to radio apparatus and more particularly to a coupling device adapted to be used in receiving circuits of the regenerative type.

5 An object of this invention is to sharpen the tuning in a radio receiving set. Another object is to provide more efficient regeneration in a radio receiving set.

10 A feature of the invention is a three-coil transformer comprising windings having low distributed capacity which for convenience are represented in the attached drawing as the type commonly called honeycomb coils angularly disposed forming substantially three sides of a triangle so that each coil is in inductive relation to the other two coils.

15 In regenerative circuits of the type heretofore generally used having a three-coil transformer, the third coil, commonly called the tickler coil, connected in the plate circuit of the space discharge device is placed in inductive relationship to the secondary which is connected in the grid-filament circuit of 20 the device. The purpose of this coil is to feed back energy into the secondary circuit from the plate circuit to partly compensate for the energy lost due to the effective resistance of the coils and the space discharge device. This feed-back of energy has the effect 25 of the introduction of negative resistance which is added to the secondary circuit in such an amount that it will compensate, or nearly compensate, for the positive resistance of that circuit. When the condition is 30 reached wherein the negative resistance is equal to or greater than the positive resistance the circuit becomes unstable and is in an oscillating condition as any current applied would continue flowing or tend to build 35 up indefinitely. The disadvantage of this type of coupling is that the amount of feed-back which it is possible to obtain without bringing the circuit into an oscillating state 40 is limited to that necessary to overcome the secondary losses which are small in respect to the primary losses. Furthermore, the effect of the feed-back reaching the primary circuit, in which the losses are the greater and 45 the tuning broad due to the antenna, ground and radiation resistances, is to introduce additional positive resistance into this circuit which adds to these losses and broadens the tuning further.

55 By means of the transformer described in

connection with this invention, regeneration is accomplished by magnetic coupling between the tickler coil and the primary circuit, as well as between the tickler coil and the secondary circuit. The negative resistance 60 which is added to the primary circuit by this method will reduce the total resistances and thereby decrease the losses and increase the sharpness of tuning in that circuit. Consequently, as it is not necessary to feed back as 65 much energy into the secondary circuit as heretofore, the negative resistance of this circuit will be numerically less than the positive resistance and it will not reach an oscillating condition.

70 Although the novel features which are believed to be characteristic of this invention will be pointed out with particularity in the claims appended hereto, the invention itself, 75 its objects and advantages, the mode of its operation and details of its organization will be better understood by referring to the following description taken in connection with the accompanying drawing in which Fig. 1 is a plan view of the type of three coil transformer heretofore generally used in regenerating circuits; Fig. 2 is a plan view of one type of transformer embodying this invention; Fig. 3 is a plan view of a more practical form of transformer embodying this invention and Fig. 4 shows diagrammatically a circuit in which this transformer may be 80 used.

85 In Fig. 1 the primary coil 2 and the secondary coil 3 are placed in inductive relationship 90 to one another and the feed-back or tickler coil 4 is placed in inductive relationship to coils 2 and 3 in the manner heretofore generally used. If high frequency currents flowing 95 in the windings of primary coil 2 induce a magnetic flux in the direction indicated by the dotted arrow associated with coil 2, the effect of a portion of this flux passing through secondary coil 3 will be to induce currents in the windings of coil 3 in such a direction 100 that the flux induced by these currents will be in the direction indicated by the dotted arrow associated with coil 3 which, it should be noted, is in a direction opposed to that of the flux of coil 2. If the currents induced in coil 3 by the action of the flux of coil 2 are to be 105 augmented by similar currents induced in coil 3 by the action of the flux of tickler coil 4, it is obvious that the flux of coil 4 must pass through coil 3 in a similar direction to that 110

taken by the flux from coil 2; that is, opposed to the direction of the flux of coil 3. Therefore the dotted arrow associated with coil 4 indicates the direction of the flux induced by currents flowing in the windings of tickler coil 4. However, since it is apparent from the relative positions of coils 2 and 4 that the portion of the flux of coil 4 which passes through coil 2 passes through in a direction similar to that taken by the flux induced by the currents initially flowing in coil 2, the effect of the flux of coil 4 upon coil 2 will tend to induce currents in the windings of coil 2 in a direction opposite to those initially flowing therein, and the result will be a reduction of the value of the resultant current. If the positions of any of the coils are interchanged the same relationship hold; and, if the direction of the current flowing in the windings of coil 4 be reversed, the effect will be that the currents flowing in primary coil 2 will be augmented while the currents flowing in secondary coil 3 will be reduced. It therefore follows that with this more or less parallel arrangement of the coils the benefits accruing through regeneration can occur in either the primary or the secondary circuits, but never in both, the other circuit being affected detrimentally.

In Fig. 2 which shows one form of the present invention, the primary coil 2, secondary coil 3 and tickler coil 4 are arranged in triangular relationship with their axes displaced at an angle of 120° from one another and meeting at a common central point. The directions of the magnetic fluxes induced by currents flowing in the windings of the coils are represented by arrows associated with the respective coils. Owing to the nearly opposing directions of the fluxes it is apparent that the flux set up by currents flowing in any one of the coils induces currents in the remaining two coils which are in the same direction as the currents originally flowing in these coils and, therefore, augment the currents in both coils simultaneously, in contrast to the effects resulting from the arrangement of Fig. 1.

Owing to the condition that the number of turns in the winding of primary coil 2 is usually less than those in the winding of secondary coil 3 and also to the condition that the losses existing in the primary circuit are greater than those present in the secondary circuit, it is usually advisable to place primary coil 2 in closer inductive relation to tickler coil 4 than that existing between secondary coil 3 and tickler coil 4. It has also been found that when this type of transformer is used the coupling required between primary coil 2 and secondary coil 3 for most successful operation is considerably less than that which is desirable when an arrangement like that of Fig. 1 is used.

Fig. 3 shows arrangement of the coils

in which these conditions have been satisfied and this constitutes one practical form which the invention may take. Primary coil 2 is in close inductive relationship with tickler coil 4, whereas the coupling between secondary coil 3 and each of the other two coils is relatively weak. It can be seen from the opposing directions of the arrows that the directions of the fluxes are similar to those of Fig. 2 and that the action is the same.

In Fig. 4 the antenna circuit comprising antenna 1, primary coil 2 of receiving transformer 5 and variable condenser 6 is loosely and variably coupled to the secondary circuit by means of the secondary 3 of the receiving transformer. The tuned secondary circuit consists of secondary 3 and variable condenser 8, which is adapted to be adjusted to bring the circuit into resonance with the incoming waves. The energy in this circuit is amplified in a radio frequency amplifier comprising space discharge device 7 having its input circuit connected across condenser 8 and its output or plate circuit connected to the primary 9 of radio frequency transformer 10. Secondary 11 of this transformer is connected in the input circuit of the second space discharge device 12 which is adapted to operate as a detector. The output or plate circuit of this second space discharge device 12 includes a coil 4 in inductive relationship to both primary coil 2 and secondary coil 3 and the primary of audio frequency transformer 13. The secondary of transformer 13 is included in the input circuit of the first space discharge device 7, in which the audio frequency energy from the detector 12 is amplified. Receiver 14, herein shown as a loud speaking horn, although it may take any other form desired, is included in the plate circuit of this amplifier 7 and transforms the audio frequency energy into sound waves.

Space current and filament heating current for tubes 7 and 12 is obtained from source 17 by means of transformer 15 and rectifying device 16 in the manner described in my copending application Serial No. 751,202, filed November 21, 1924, which features are not essential to this invention and will not be described in detail here as any other source or sources of space and heating current may be used.

In the operation of this system high frequency impulses received in the antenna circuit are transferred to the input circuit of the radio frequency amplifier 7 by means of transformer 5 and are amplified in this tube. The amplified signals are then impressed upon tube 12, a portion of the output energy of which consists of audio frequency energy brought about by the detector action of the tube and another portion of which is similar to the impressed signals except that it is in amplified form. This high frequency component of the energy in the plate circuit is

then impressed upon both the primary and the secondary coils of transformer 5 by means of feed-back coil 4 thereby increasing the amount of energy flowing in the antenna circuit and further strengthening the signals received. At the same time the energy flowing in the secondary circuit will be increased directly by transfer between coils 4 and 3 and also indirectly by transfer between coils 4, 2 and 3. The coupling between tickler coil 4 and the secondary coil 3 is much looser than that between the tickler coil and the primary 2, in order that the negative resistance of the secondary circuit will not be increased to such an extent that the operation will become unstable, when the resistances of the primary circuit are reduced to the optimum value. The advantage of this will be apparent when it is remembered that the secondary circuit is ordinarily of low loss, or high time constant, whereas the primary circuit is of high loss, or low time constant. A comparatively small amount of energy fed back into the secondary circuit would tend to produce unstable operation, as above set forth, whereas a much larger amount of energy fed back into the primary circuit would only tend to increase the signal strength and would not cause the operation of the circuit to become unstable. The low frequency component of the energy in the plate circuit of tube 12 is impressed upon the grid-filament circuit of tube 7, by audio frequency transformer 13, where it is repeated and amplified before operating a sound reproducing means 14. Although this circuit has been shown as a reflex regenerative circuit by way of illustration, the transformer arrangement 5 is equally applicable to a single tube receiver wherein the tube operates as a detector only, or to any other transformer coupled circuit in which regeneration is made use of to reduce the losses in the primary or secondary circuits or to increase the selectivity of the system.

Although the coils composing the transformer 5 have been shown in Figs. 2, 3 and 4 as

honeycomb coils, the invention is not limited thereto, but is equally applicable to other coils wound in a different manner, which may be mounted in the same general relationship. 50

What is claimed is:

1. A regenerative radio receiver comprising a plurality of space discharge devices connected in tandem, a wave receiving circuit, an input circuit for the first of said space discharge devices and an output circuit for the last device, and means for inductively coupling said output circuit additively to said wave receiving circuit and said input circuit in such a manner that more energy is transferred from said output circuit to said wave receiving circuit than to said input circuit. 55

2. A regenerative radio receiver comprising a wave receiving circuit, a plurality of space discharge devices connected in tandem, an input circuit for the first of said space discharge devices, and an output circuit for the last device, coils in each said wave receiving circuit, said input circuit and said output circuit, and means for inductively coupling said coils additively, whereby the amount of energy transferred from said output circuit coil to said wave receiving circuit coil is greater than that transferred to said input circuit coil. 60

3. A regenerative radio receiver comprising a wave receiving circuit consisting of an antenna, an inductance coil, a variable condenser and a ground connection; a plurality of space discharge devices connected in tandem, an input circuit for the first of said space discharge devices and an output circuit for the last device, a coil in each said input circuit and said output circuit, means for inductively coupling said coils additively, in such a manner that more energy is transferred from said output circuit coil to said wave receiving circuit coil than to said input circuit coil. 75

In witness whereof, I hereunto subscribe my name this 30th day of October A. D., 1924.

DONALD F. WHITING.
